TAP DRIVER

Henry P. Boggis, Shaker Heights, Ohio

Application March 28, 1944, Serial No. 528,497

4 Claims. (Cl. 279—56)

1

This invention relates as indicated to tap drivers and in general to tool holders adapted to directly embrace, in driving communication, tools such as taps which are provided with a cylindrical shank and generally a polygonal terminal portion through which the driving forces are transmitted. The cylindrical portion of the tool is required to be maintained in axial alignment with the axis of rotation of the driving means such as a spindle of a drill press or like equipment. The cylindrical surface of the tool by which such axial alignment may be maintained does not provide for the transmission of the driving force from the holder to the tool, and accordingly the tool is generally provided at its non-operating end with a polygonal surface which may be square, rectangular, or in the form of a flat tongue.

In the manufacture of tools of this character, it is quite difficult to maintain in alignment the axis of the cylindrical portion of the tool and the axis of the polygonal portion through which driving communication is established. If the holder for the tool is provided with truly axially aligned portions adapted to embrace the cylindrical and polygonal portions of the tool respectively, the clamping forces to which the tool is subjected in being fixed in the holder will result in the setting up in the tool of forces which may result in the end thereof being forced out of line, or the setting up of internal stresses in the tool itself which are highly undesirable.

It is a principal object of my invention, therefore, to provide a structure which will not only engage the tool in its cylindrical portion and maintain the tool coaxially with the axis of rotation of the holder, but at the same time, embraces the polygonal portion of the tool and transmits the driving force thereto without placing the tool under any of the objectionable stresses above mentioned.

Other objects of my invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing—

Fig. 1 is a side elevational view partially in section along a vertical plane passing through the

2

longitudinal axis of the tool and showing one embodiment of my invention;

Figs. 2, 3 and 4 are transverse sectional views of the structure illustrated in Fig. 1, taken on planes respectively indicated by the lines 2—2, 3—3, and 4—4;

Fig. 5 is a perspective view of the floating driven block which is one of the parts of the assembly illustrated in Fig. 1; and

Fig. 6 is a perspective view of the floating driver block likewise comprising one of the parts of the assembly illustrated in Fig. 1.

Referring now more specifically to the drawing and more especially to Fig. 1, the structure here illustrated comprises a body 1 which is generally cylindrical in form, and to the rear end of which there is integrally connected a taper or straight shank 2 terminating in a flattened end 3. The shank 2 is coaxial with the axis of the cylindrical portion 1 of the body and ground to a suitable taper such as a Morse taper so that the tool may be held in a conventional drilling or tapping machine.

The forward end 4 of the body 1 is coniform on its interior and thus adapted to receive a coniform collet 5. The external surface 6 at the end of the body 1 is a ground cylindrical surface adapted to be closely embraced by the ground surface 7 on the inside of the nut 8. The open end 30 of the nut 8 is threaded and in threaded engagement with threads formed at 9 in an intermediate area on the body 1. Openings 10 are provided at circumferentially spaced points on the nut 8 and adapted to receive a tool such as a spanner wrench to assist in applying and removing the nut 8 on the body 1.

The nut 8 at its forward end is provided with an inwardly extending flange 11 having a coniform shoulder 12 adapted to engage a complementary coniform shoulder on the collet 5.

The collet 5 is centrally provided with a cylindrical opening adapted to closely embrace and telescopically engage the cylindrical portion 13 of a tool such as 14 which is illustrated as a tap. The non-operating end 15 of the tool is polygonal in cross-section, the illustrated embodiment being square as most clearly shown in Fig. 3.

The end 15 of the tool is closely embraced in a corresponding opening formed centrally in the floating driven block 16 whose outer periphery is cylindrical and of a diameter slightly less than the inside diameter of the body 1. In axial alignment with the floating driven block 16 is a cylindrical floating driver block 17, the latter being mounted for relative rotatable and axial movement on a

pin 18 carried by the body and arranged so that the axis intersects the axis of the body 1 at right angles.

As most clearly illustrated in Figs. 5 and 6, the contiguous faces of the members 16 and 17 are provided with a complementary tongue and groove connection which, in the illustrated embodiment, includes a tongue 19 formed on the member 16, and a groove 20 on the member 17. The member 16 has a central aperture 21 extending therethrough from the bottom of the opening which is adapted to receive the end 15 of the tool.

It should be pointed out that the opening in the member 16 for the reception of the end 15 of the tool may be a stepped opening so as to accommodate tools having ends of different sizes or it may be desirable to provide a series of interchangeable members 16 each provided with a different opening for the reception of such different sizes and shapes of tool ends as the holder may be required to accommodate.

From the foregoing description, it will be observed that when a tool such as a tap 14 is assembled in the holder, the ground complementary cylindrical surfaces on the inside of the nut and the forward end of the body, and the ground complementary coniform surfaces on the periphery of the collet and the inside end of the body, and the ground complementary cylindrical surfaces on the outside of the tool and the inside of the collet, make it possible to very accurately maintain the axis of the tool in alignment with the axis of the holder.

As previously indicated, the driving end 15 of the tool may, however, have its axis out of alignment with the axis of the cylindrical surface 13. Any such misalignment will be automatically compensated for by the floating driving connection which comprises the members 16, 17, and the pin 18.

By this construction, driving communication is established between the holder and the end of the tool without subjecting the tool to bending stresses and the like which might otherwise result from misalignment between the axes of the cylindrical portion 13 and the terminal portion 15 of the tool.

Other modes of applying the principle of the invention may be employed, change being made as regards the details described, provided the features stated in any of the following claims or the equivalent of such be employed.

I, therefore, particularly point out and distinctly claim as my invention:

1. A tool holder comprising a body having a driving shank; means for maintaining a tool in substantially axial alignment with said shank; and a floating driving connection between said body and the tool, comprising a transversely arranged pin in said body, a driving block movably mounted on said pin, and a floating driven block adapted to engage the end of the tool, and a complementary tongue and groove connection between said driving block and driven block.

2. A tool holder comprising a body having a driving shank; means for maintaining a tool in substantially axial alignment with said shank; and a floating driving connection between said body and a polygonal terminal portion of the tool, comprising a pin in said body, the axis of which lies in a plane normal to the axis of said body,

a driving block mounted for rotatable and axial movement on said pin, said block provided with a face normal to the axis of said body, and a floating driven block adapted to closely embrace the polygonal terminal of the tool and presenting a face closely adjacent and substantially parallel to the face on said driving block, and a complementary tongue and groove connection on said faces.

3. A tool holder comprising a body including a tapered driving shank; means for maintaining a tool in substantially axial alignment with said shank comprising a collet having coniform telescopic engagement with said body and substantially cylindrical telescopic engagement with the tool, and a nut threaded on said body and having close-fitting cylindrical telescopic engagement therewith and engageable with said collet to move said collet and body relatively axially; and a floating driving connection between said body and a polygonal terminal portion of the tool, comprising a pin in said body, the axis of which lies in a plane normal to the axis of said body, a driving block mounted for rotatable and axial movement on said pin, said block provided with a face normal to the axis of said body, and a floating driven block adapted to closely embrace the polygonal terminal of the tool and presenting a face closely adjacent and substantially parallel to the face on said driving block, and a complementary tongue and groove connection on said faces.

4. A tool holder comprising a body having a driving shank, means for maintaining a tool in substantially axial alignment with said shank, axially adjacent driving and driven blocks loosely fitting within said body, said blocks having a complementary tongue and groove connection between them for permitting relative transverse movement thereof in said body, said driven block being formed with a socket for driving engagement with the end of the tool, and means supporting said driving block for rotation in unison with said body and for transverse movement in said body along a line angularly disposed with respect to the line of transverse movement permitted by the tongue and groove connection of said blocks.
